CLEANING APPARATUS

Erwin E. Franz, Cranford, N. J., assignor to Western Electric Company, Incorporated, New York, N. Y., a corporation of New York

Application June 5, 1942, Serial No. 445,917

2 Claims. (Cl. 15—24)

This invention relates to cleaning apparatus, and more particularly to apparatus for cleaning articles, such as terminals of electrical units.

Terminals of electrical units to which lead wires of coils or other parts of the units are connected by means of soldering, are in some instances required to be cleaned to remove solder flux or other foreign particles therefrom, which may lessen or prevent electrical connections with the terminals during the use of such electrical units. The method of cleaning such terminals depends upon the contour and the arrangement of the terminals on the electrical units, and when a plurality of terminals is present it is important that they each be thoroughly clean.

An object of the invention is to provide a simple, efficient and highly practical apparatus for cleaning articles, particularly terminals of electrical units.

With the above and other objects in view, the invention comprises cooperating brushes movable relative to an article disposed therebetween and continuously supplied with a cleaning fluid to clean the article.

Other objects and advantages will be apparent from the following detailed description when considered in conjunction with the accompanying drawings, wherein

Fig. 1 is a vertical sectional view of the apparatus, portions thereof being shown in elevation;

Fig. 2 is a top plan view of the apparatus;

Fig. 3 is a horizontal sectional view taken along the line 3—3 of Fig. 1;

Fig. 4 is a horizontal sectional view taken substantially along the line 4—4 of Fig. 1, and

Fig. 5 is a fragmentary vertical sectional view taken along the line 5—5 of Fig. 1.

Referring now to the drawings, attention is first directed to Fig. 1, which illustrates a housing 10 which is cylindrical in general contour and is substantially closed at its lower end by a base 11 and at its upper end by a cover 12. The base 11 rests upon any suitable support, such as a table 14, and is recessed to receive a supply tank 15 for a cleaning fluid 16, the latter being of a suitable type such as varsol. The supply tank 15 may be of any desired length and extend through an aperture 17 in the table. A tubular outlet 18 for the housing 10 has its upper end disposed in an aperture 19 of the base 11 and extends downwardly a desired distance into the tank 15. A receiving tube 20 also extends through an aperture in the base 11, the lower end of the tube terminating, however, a short distance beneath the base within the tank 15.

The upper end of the tube 20 communicates with a passageway 21 in an element 22 which is of the contour illustrated in Figs. 1, 3, 4 and 5. The element is formed to be received in the housing 10, particularly in a reduced upper portion 25 in the walls thereof, and rest upon an annular shoulder 27 as shown in Fig. 1.

Returning now to the passageway 21, which is vertical, it will be observed, by viewing Figs. 1 and 4, that this passageway communicates with a horizontal passageway 29 and then with a vertical passageway 30, the latter being in communication with a compartment 31 in which pump members 32 and 33 are disposed.

Attention is now directed to the power means for driving the pump members. These members, as will be apparent by viewing Figs. 1 and 4, are of the gear type adapted to receive a fluid from the passageway 30 and transport the fluid in quantities, in the cavities between the teeth of the members, in opposite directions about the wall of the compartment 31 to the opposite side thereof. Thus the members are interengaged and the driving of one member will result in simultaneous driving of both members. The pump member 32 is mounted upon a shaft 35 (Figs. 1, 3 and 5) which is suitably journaled in bearing portions of the element 22 passing through a hollow portion 36 of the element in

which gears are disposed. The gears referred to include a gear 37 fixed to the shaft 35, another gear 38 being mounted for free rotation upon the shaft. Another shaft, which may be termed a drive shaft, is indicated at 39 and is disposed in suitable bearings in the element 22 parallel with the shaft 35, as shown in Fig. 5. The shaft 39 does not project through the element 22, as does the shaft 35, but stops short thereof to allow for a small shaft 40 for the pump member 33 to be journaled in the same bearing therewith. Gears 42 and 43 are disposed upon the shaft 39, the former being free to rotate thereon while the latter is fixed thereto. It will be noted that the fixed end gears 37 and 43 are of the single type, while the free intermediate gears 38 and 42 are of the double type. A suitable power means, such as a motor 44, is operatively connected, as at 45, to the shaft 39 and when the shaft 39 is rotated the gear 43 is driven thereby, driving the gear 38 which is in interengagement therewith and free to rotate upon its shaft 35. The gears 38 and 42 being in interengagement with each other and the gears 42 and 37 being also in interengagement with each other,

complete a driving connection from the motor

44 through the shaft 39, the gear 43, the gear 38, the gear 42, the gear 37, to the shaft 35. Thus the pump member 32 is driven and during its rotation the motor member 33 is driven.

Attention is now directed to the exit side of the pump members, where a passageway 47 extends vertically from a position in communication with the compartment 31, where it receives the fluid 16, to a lateral passageway 48 provided for the continued travel of the fluid to a cleaning unit indicated generally at 50. The cleaning unit includes an oscillating element 51, which is hollow, to receive an annular outer brush 52 with bristles 53 extending inwardly to a given cylindrical limit, leaving a cylindrical hollow central portion filled by an inner brush 54. The latter is composed of a multiplicity of bristles, extending substantially radially so that their outer ends will meet the inner ends of the bristles of the brush 52, supported by a member 55 which is removably disposed in a central aperture 56 of the element 51. The member 55 also has an integral portion 57 as shown in Fig. 1 and receivable in a recess of the element 51. Apertures 57' are also provided therein adjacent the meeting edges of the brushes. Although the member 55 may be removed from its aperture, there is a sufficient frictional holding force present to hold the brush for movement with the element.

The element 51 of the unit 50 has a shaft portion 58 provided with longitudinal grooves 59 therein communicating at their upper ends with passageways 60 in alignment with the juncture or meeting ends of the two brushes 52 and 54, the lower ends of the grooves 59 communicating with an annular recess 61 in the shaft portion. The recess 61 communicates with the passageway 48 so that there may be a continuous passageway for the fluid from the pump members to the brushes.

Attention is at this time directed to the forward or left end of the passageway 48 which continues beyond the shaft portion 58 of the unit 50 which is closed by a plug 63. Adjacent the plug 63 is a reduced or recess portion 64 in the element 22, this recess being provided for the supplying of the cleaning fluid 16 to the housing and tank by the removal of a plug 66 from the adjacent wall of the housing 10. A passageway 67 is also provided in the element 22 which leads from the upper portion of the element beneath the unit 50 to the recess 64.

The lower end of the shaft portion 58 has a reduced portion or end 68 which extends beneath the element 22 to receive a lever arm 70 (Figs. 1 and 4). A link 71 is mounted upon the outer end of the arm 70 to operatively connect the arm to an eccentric or crank arm 72, the latter being mounted upon the shaft 35 beneath a cover plate 74 which supports the pump members 32 and 33 and closes the compartment 31 in which they are disposed.

The cover 12 is formed to support the motor 44 and apertured to receive its connection with the shaft 39. An aperture 76 of the type illustrated in Fig. 1 is formed in the cover in central alignment with the unit 50 and of a contour to receive an electrical unit 77 and accurately position terminals 78 and adjacent portions thereof between the brushes 52 and 54. The portion 57' serves as a stop and a support for the electrical unit 77. In the present embodiment the terminals 78 are disposed in circular arrangement and extend a given distance beneath the body

of the unit. Furthermore, the terminals are circular in cross-section, they being hollow and having received leads or conductors therein which have been soldered in place by the dipping of the terminals in a solder bath not shown.

5 A safety feature is incorporated in the apparatus and made a part thereof. This feature includes a door 80 pivotally mounted at 81 and of the general contour illustrated in Fig. 2, with an aperture 82 to receive the unit 77 and be in direct alignment with the aperture 76. If the existing friction between the brushes and the terminals should cause ignition of the cleaning fluid during the operation of the apparatus, the electrical unit may be withdrawn and the heat of the flame would melt a fusible link 85, which normally holds the door 80 in the open position, against the force of a spring 86. The spring has one end fixed at 87 to a portion of the housing 10 and the other end connected at 88 to a projecting end of the door 80. The fusible link has one end fixed to a pin 89 mounted upon the cover 12, the other end being connected to a pin 90 which is mounted upon the door 80 and projects through an elongate aperture 91 in the cover, the ends of the aperture limiting the movement of the pin and controlling the open and closed positions of the door.

20 During the operation of the apparatus the motor 44 drives the shaft 39, and through the gears 43, 38, 42 and 37, the shaft 35 is driven to drive the pump member 32 and, through their interengagement, the pump member 33. At the same time, rotation of the eccentric 72 will cause an oscillatory movement to be imparted to the unit 50 through the link 71 and the arm 70. During this oscillatory movement of the unit 50 the fluid 16 or quantities thereof are drawn continuously 25 through the tubular member 20 from the tank 15, through the passageways 21, 29 and 30 to the compartment 31, where the fluid is divided into two portions by the pump members and passed around the walls of the compartment to the outlet end thereof. From this point the fluid is forced through the passageways 47 and 48 into the recess 61, and upwardly through the grooves 59 and the passageways 60 to the brushes 52 and 54 at their meeting edges. With the door 80 normally open, an article such as the electrical unit 77 may be lowered through the apertures 76 and 82 until the terminals 78 thereof are positioned at the juncture of the brushes. The oscillatory movement of the unit will impart the same motion to the brushes, and due to the structure of the latter the bristles thereof will scrape over all portions of each terminal to loosen and remove therefrom the undesired particles present thereon. Furthermore, the cleaning fluid 16, in being constantly forced upwardly in direct alignment with the article or the portions thereof being cleaned at the juncture of the two brushes, operates therewith in the cleaning operation and the removal of the particles freed from the article or terminal during the cleaning operation. Thus the fluid used during the cleaning operation overflows the unit and passes back into the supply in the spaces provided upon each side of the element 22, as clearly illustrated in Figs. 3 and 4. 30 Any solid particles which have been removed or substances which will be of greater cleaning fluid, will pass downwardly in the fluid and eventually settle at the bottom of the tank 15, they having passed through the outlet tube 18. The tube 20 having its lower end positioned above the lower

end of the tank 15, will receive its supply thereby and at a position out of association with the used fluid wherein the foreign particles may be present. This operation may be continued, the cleaning operation repeated by the placing of an article through the apertures 76 and 82, its removal and another article disposed in place.

It will, therefore, be apparent that friction elements such as the elements are formed to engage all portions of an article to be cleaned at the juncture thereof and that a cleaning fluid is constantly supplied thereto at the said juncture of the friction members, the cleaning fluid not only assisting in the cleaning operation to remove the particles resulting from the operation but returning the fluid in which the particles are disposed to a portion of the supply spaced from that portion adjacent the pump members.

Although specific improvements of the invention have been shown and described it will be understood that they are but illustrative and that various modifications may be made therein without departing from the scope and spirit of this invention as defined by the appended claims.

What is claimed is:

1. A cleaning apparatus comprising a cleaning unit including a cup-shaped element, with apertures disposed in a circular arrangement in the bottom portion thereof, and opposing brushes with their free ends substantially meeting adjacent the apertures, a shaft, having longitudinally extending grooves therein communicating with the apertures, supporting the unit, means to support the shaft for movement about its axis, a reservoir for a supply of cleaning fluid, a feeding passageway leading from the reservoir to the grooves in the shaft, operable fluid circulating means disposed in the feeding passageway to force fluid from the supply through the

passageway, the grooves, the apertures and through the brushes to overflow the open end of the element, a return passageway to receive the fluid overflowing from the element and return it to the reservoir, power means to operate the circulating means, and means to operatively connect the shaft to the power means to cause oscillation of the shaft and unit to cause the brushes, aided by the fluid traveling therethrough, to remove foreign particles from an article disposed between the brushes.

2. A cleaning apparatus comprising a cleaning unit including a cup-shaped element, with apertures disposed in a circular arrangement in the bottom portion thereof, and opposing brushes with their free ends substantially meeting adjacent the apertures, a shaft, having longitudinally extending grooves therein communicating with the apertures, supporting the unit, means to support the shaft for movement about its axis, a reservoir for a supply of cleaning fluid, a feeding passageway leading from the reservoir to the grooves in the shaft, operable fluid circulating means disposed in the feeding passageway to force fluid from the supply through the passageway, the grooves, the apertures and through the brushes to overflow the open end of the element, a return passageway to receive the fluid overflowing from the element and return it to the reservoir, power means to operate the circulating means, means to operatively connect the shaft to the power means to cause oscillation of the shaft and unit to cause the brushes, aided by the fluid traveling therethrough, to remove foreign particles from an article disposed between the brushes, and means having an article receiving aperture therein to guide the article between the brushes.

ERWIN E. FRANZ.
